10 Claims. (Cl. 66—175)

This invention is concerned with fabrics formed by interconnecting loops of yarn and garments fashioned therefrom. It is particularly concerned with fabrics useful for garments worn under pressure, such as anti-G suits, elasticized clothing, etc., and methods and mechanism for fabricating them.

The human body is conditioned to the atmospheric pressure of approximately fifteen pounds per square inch experienced at the earth's surface. For flight into the less dense stratosphere and remote outer space this pressure must be substantially maintained if the traveler is to survive.

Two devices are used to maintain an environment of substantially standard atmospheric pressure about a man traveling in rarefied atmosphere. One is to pressurize the interior of the vehicle in which he is traveling. The other is to provide him with a pressurized suit. Such suits are also used for pilots and crew of aircraft maneuvering at supersonic speeds to protect them against the effects of inertia upon their bodies. In such application these garments are referred to as anti-G suits.

It has been the practice to provide these garments in the form of a rubber bladder which may be inflated to the pressure required for protection. For relatively low pressure differentials this inflated suit technique is satisfactory. When the pressure difference is significant, however, it is necessary to contain the pressurized bladder within a casing or cover to prevent it from bursting.

Ordinary woven cloth has been used as such a cover. It satisfies the requirement of containing the bladder, but has the property of becoming extremely taut under pressure with the result that the suit becomes rigid and its wearer loses the power of effective movement of his limbs, becoming practically helpless. Since knitted fabric has the quality of greater inherent flexibility than woven cloth, attempts have been made to form suits from a combination of rubber tubes adapted to the shape of the different limbs and torso of the body and to encase these tubes in knitted sleeves. Even these structures, however, become rigid and lock once significant pressure is applied to the tube-like bladders.

Accordingly, a primary objective of the present invention is to provide a more satisfactory and less rigid pressurized garment, especially an anti-G or space suit, and an improved fabric for covering such garments.

These and related objectives are accomplished in one embodiment of the invention which features, as an illustrative example, an anti-G or space suit comprised of a plurality of substantially tubular shaped bladder portions each covered by a knitted fabric wherein the wales of the looped structure run substantially circumferentially around the tube instead of longitudinally along its length. In one modification of the invention rib wales are inserted at critical locations to define areas where flexibility is desired to accommodate bending of joints etc.

Other modifications and features of the invention will be apparent from the following description and reference to the accompanying drawing, wherein:

FIG. 1 is a diagrammatic representation of a portion of a knitted fabric adapted to cover a tubular bladder after the manner of the invention;

FIG. 2 is a representation of a portion of a tubular bladder covered by a looped fabric;

FIG. 3 illustrates diagrammatically how a flat knitted

2

fabric may be formed into a seamless covering for a tubular bladder; and,

FIG. 4 is a diagrammatic representation of a garment embodying features of the invention.

FIG. 1 shows a portion of a length of knitted fabric 10 having a number of rib wales 12 separated by successive wales 14 of plain knit loops. Such fabric may be produced with selvaged sides and a raw edge of loops at top and bottom, as shown at course 16 or with a starting selvage, in a manner well known in the art, by reciprocatory knitting on a links-and-links or V-bed knitting machine or flat bed equipment. It may be converted into a seamless tube, as represented at 18 in FIG. 2, by drawing an end of yarn from the first course 16, or the last course 20, through the loops of both first and last courses in the manner shown in FIG. 3, and thereby producing a joining course 22.

This technique is also known to those skilled in the art of knitting. It comprises drawing a needle 24 carrying a loose end 26 of yarn behind adjacent shoulders of adjacent raw loops of one course, e.g., 16, and then moving over one wale and similarly drawing the end 26 behind adjacent shoulders of adjacent raw loops of the other course, e.g. 16. The process is repeated and results in a course 22 of loops, as shown in FIG. 3, which correspond exactly to the loop structure of the remainder of the fabric. When the course 22 is completed the end 26 may be tied off and fused with the other free end of yarn leading from the fabric to complete the seamless tube such as 18 in FIG. 2.

The invention has discovered that, if a seamless tube 18 produced in this manner is used to encase an inflated bladder 28, as shown in FIG. 2, the complete assembly can be bent with considerably less effort than a similar arrangement having a covering of either woven fabric or the conventional knitted sleeve, with wales running longitudinally of the tubular bladder 28, which has hitherto been used for this purpose.

A protective shield 30 comprised, for example, of a fabric woven or knitted from a "stretch yarn" such as Helaanca, may be inserted between the bladder 28 and the knit covering 18. This shield absorbs some pressure, prevents the knitted fabric from chafing against the bladder, and helps to contain it from bulging through the open mesh of the knitted loops. Various sizes of loop structure and types of yarn have produced satisfactory covers 18. One successful combination has been a structure of approximately 16 loops per square inch knit with a single end of pound test braided Dacron. Another protective safeguard against chafing of the yarn is to immerse it in a solution of a lubricating substance such as lanolin, silicone, etc.

The seamless fabric casing may have a number of rib wales 12 inserted in the areas where bending is to take place; or, it may be fabricated by plain Jersey knitting throughout. If rib wales are used, they may commence several inches away from the joint, on either side, and occur every few inches at first, then more closely together until they are less than an inch apart at the joint. This builds into the fabric structural reference lines for bending purposes. To accentuate this effect the fabric is drawn over the bladder with the rib wales facing inward so that they are tighter against it than the surrounding fabric and thus provide greater restriction and, therefore, a creasing capability.

The invention is not limited to the specific embodiments and features shown and described, but is to be given the scope of the following claims.

70 What is claimed is:

1. A pressurized garment comprising: a plurality of tubular members each including a tubular bladder; and,

a seamless looped fabric encasing said bladder, the loops of said fabric being arranged in wales having a longitudinal direction circumferential of said bladder.

2. The invention according to claim 1, and wherein said looped fabric comprises a knitted structure.

3. The invention according to claim 2, and wherein said knitted structure includes a combination of plain and rib wales.

4. The invention according to claim 3, and wherein said rib wales protrude from the surface of said fabric inwardly against said bladder.

5. The invention according to claim 1, wherein an expandable fabric liner is inserted between said tubular members and said looped fabric.

6. A garment which comprises a plurality of inflatable portions arranged to encase human limbs and a covering which includes separate seamless knitted sleeves for separate ones of said portions, each of said sleeves having a wale structure running in a circumferential direction, said wale structure including one or more rib wales protruding against its respective inflatable portion.

7. A fabric garment having a plurality of limb covering sleeves each comprising a mesh structure with rib wales protruding from their inside surface, said rib wales being arranged to lie in a longitudinal direction which is circumferential of their respective sleeves.

8. A pressurized garment which comprises a plurality of tubular members, each including: a tubular bladder; a seamless looped fabric encasing said bladder, said

4
fabric having its component loops arranged in wales running circumferentially around said bladder.

9. A garment which comprises: an inflatable member having a plurality of tubular portions; and, a covering for each of said plurality of portions, said covering comprising knitted fabric structures having wales running circumferentially of said tubular portions.

10. In a garment adapted to provide pressurized protection for a human body a flexible sleeve portion comprising: a tubular inflatable bladder member; a knitted covering for said bladder; said covering having a combination of plain and rib knit wales running circumferentially of said tubular member; said rib knit wales protruding from said plain knit wales in the direction of said bladder thereby providing creases to define flexible portions in said bladder when it is inflated into pressurized contact with said covering.
